NEWTON W. MATTHEWS, OF FULLERTON, CALIFORNIA.

SUCTION-OPERATED SIGNAL FOR AUTOMOBILES.

Application filed June 18, 1928. Serial No. 286,349.

This invention relates to traffic signals and more particularly to direction indicating signals adapted for attachment to automobiles.

5 The primary object of the invention is to provide a direction-indicating signal which shall be operable by the suction of an automobile engine. A further object is to provide such a signal wherein the only manual 60 operation required will be the setting of a control for the desired direction indications.

An additional object is to provide in combination a fully automatic control for attaining a stop-signal position of the same signalling member giving the direction-indicating 65 positions. And another object is to render the mechanism positively operable to return the signal element to the original or neutral position.

20 The invention for accomplishing these objects resides essentially in a rotary or swinging signal member in combination with a suction creating means, such as an automobile engine, suction-communication being provided between the engine and the signal 70 for operation of the latter to assume signalling position. According to one form, the signal member is movable to a plurality of positions, such as "Right", "Left" and "Stop", through the medium of a control 75 valve which selectively applies suction through corresponding connections to actuate the signal to the respective positions.

80 Preferably the control valve is set manually for "Right" and "Left" positions, but is connected with the brake pedal for automatic shift to and from "Stop" position, manual shift to "Stop" being possible if desired. Preferably, also, the control valve includes 85 provision for applying the suction to return the signal positively to neutral position, that is non-signalling position. The invention therefore resides also in the combination of a pneumatic signal operable, for example

90 by means of engine suction, to a plurality of signalling positions, with a control device having a plurality of ducts or ports and movable to a plurality of positions for selectively applying the pneumatic energy (engine suction in the example) and thereby selectively 95 positioning the signal element.

In a specific type, the signalling device of the present invention includes a rotary member having a blade or vane fixed thereon and movable therewith; this member being

mounted upon and carried by a stationary base having at least one and preferably two blades or walls with respect to which or between which the movable vane oscillates in its various movements. The rotary member 60 carries the signal element. The stationary base and said rotary member together with their blades, cooperate to form and enclose a suction chamber with which communication is had through a plurality of ports, each 65 of which ports has connection with a common control valve which in turn is connected with the intake or suction side of the engine. The control valve includes a rotary member 70 which has a plurality of ports, these ports being adapted to be brought into selective registry with the terminals of said connections. The rotary control member is manually movable to its various positions, and is also automatically movable to "Stop" position 75 through the medium of an easily-releasing detent which is connected with the brake pedal of the machine. This detent is preferably carried on a rotary ring which is moved when the brake pedal is actuated, the ring being rotated by brake pedal actuation and thereby moving the rotary control member, the detent being readily disengaged when the rotary control member is manually actuated.

An additional suction connection leading from the control member to a fourth port on the base member of the signal device, provides for the positive return of the signal element to neutral position. Suitable ports for venting to atmosphere are also provided in the movable control member, and an electric circuit together with the necessary contacts are provided for lighting lamps in the signal element.

The invention resides further in such other novel arrangements, features of construction and combinations of parts as may be elsewhere herein disclosed.

In the accompanying drawings wherein one embodiment is disclosed merely by way of illustration of the generic invention;

Fig. 1, is chiefly a front elevation of a signal as applied to the left side of an automobile, parts however being broken away to show internal construction.

Fig. 2, is a corresponding side elevation and section as taken from line 2—2 of Fig. 1.

Fig. 3, is a front elevation of the base member and bracket of the signalling device, and

Fig. 4, is a horizontal section therethrough as indicated by the line 4—4 of Fig. 3.

Fig. 5, is chiefly a vertical section through the upper or operative portion of the rotary 5 or swinging signal element.

Fig. 6, is a vertical section through the control valve as indicated by line 6—6 of Fig. 1.

Fig. 7, is an inner face view of the rotary 10 control member.

Fig. 8, is a rear face view of the relatively fixed body member of the control valve.

Figs. 9, 10, 11, and 12, are rear views (as 15 the driver sees them) indicating the position of the movable parts of the control valve and the relation of the various ports and ducts for the "Neutral", "Right", "Left" and "Stop" positions respectively of the signal.

Fig. 13, is a detail of the detent spring on 20 the brake-operated ring which releasably engages the rotary control member of the valve and serves to move the same automatically to and from "Stop" position.

The structure illustrated includes primarily 25 a signalling arm, a signal actuating member —A— carrying the signal arm and in turn carried by a bracket —B— provided with co-operating parts, and a control valve —C— through the medium of which suction is selectively applied to operate the member 30 —A— for actuating said signal. The bracket —B— is secured as by means of bolts 14 to the post —P— which supports the automobile windshield, and is provided at its outer end 35 with a base member 15 to which is centrally secured a sleeve 17.

The casing 18 of the actuating member 40 —A— has a working fit against the base 15 and is centered thereupon for swinging movement relative thereto, by means of a centering and journaling pin 20 secured to said casing and passing through and journaled in the sleeve 17, the pin being reduced at 20' and passing through the base 15 to receive a nut 45 and washer 21 engaging the outer face of said base and securing the parts in rotative relation. A radially disposed blade 22 is carried by the casing 18 and preferably is formed integral therewith, the outer end of this blade 50 having a working fit against the base 15 and its central or axial edge being provided with a groove 22' receiving a spring 23 and a sealing strip 24, the latter being urged by the spring into sealing engagement with the outer 55 wall of the sleeve 17.

The lower outer portion of casing 18 carries the signalling arm 25 which includes a housing secured to the casing 18 as through the medium of a flange 26, said housing having its front and rear walls provided with arrow-shaped openings 27 or the like behind which colored translucent panels 28 may be placed, the whole being adapted for illumination by electric globes 29 supplied with electric current through means presently to be

described. The upper side of the casing 18 preferably is provided with a counterweight —W— to partially or entirely balance said signal arm 25.

To cooperate with the blade 22, the base 15 and the sleeve 17 have secured thereto upper and lower radially disposed blades or partitioning walls 30 and 31 respectively whose ends have a working fit against the front wall of casing 18 and whose outer axial edges are 75 provided with packing strips 32 engaging the inner circumferential wall of said casing 18, the blade 22 thus travelling between said blades or walls 30.

The housing 18, the base member 15 and the blades 22 and 31 thus enclose a suction chamber through which the blade 22 is adapted to travel under suction influences, and these influences are applied to said chamber by way of a series of suction ports —S—, 80 —L—, and —R— formed in the base 15 and respectively representing the routes for the application of suction to move the signal to the positions indicating "Stop", "Left" and "Right". In addition, a fourth port —N— 90 is provided in the base 15 where it underlies the blade 22 when the latter is in neutral or non-signalling position, this port however lying between said blade 22 and the upper fixed blade 30 when the signal is in any operative position, whereby suction may be applied through port —N— for positive return of the signal to "neutral".

In order to avoid shock at the end of the 100 return stroke, the port —N— is spaced slightly from blade 30 so that an air pocket will be formed between blades 22 and 30 and the air therein will act as a cushion, a small bleeder port 33 being provided in blade 30 to permit the slow escape of the air residue into the outer portion of the casing and to enable gravity to complete movement of the signal to neutral position. A vent hole 34 in the bottom of casing 18 prevents the trapping of 105 a dead air body in said outer casing portion and thereby prevents interference with air passage through the bleeder port.

Thus far, it will be seen that the application of suction to the signal actuating device —A— through the various ports —N—, 115 —S—, —L—, and —R—, will result in moving the blade 22 of the signal casing 18 until the respective port is covered whereupon suction is wholly or approximately cut off and the signal arm 25 remains in the position assumed, suction through ports —S—, —L—, and —R— producing "Stop" (or "Slow"), "Left" and "Right" signals respectively, and suction through port —N— resulting in positive return of the signal to the original or neutral position. These movements will be more fully described hereinafter.

Said ports —N—, —S—, —L—, and —R— are supplied by means of communicating ducts 35 formed in the base 15 and these ducts 130

communicate with conduits $-N'$, $-S'$, $-L'$, and $-R'$, of rubber or metal tubing which connect the ports $-N$, $-S$, $-L$, and $-R$ respectively with control ports $-N''$, $-S''$, $-L''$, and $-R''$ formed in the stationary body member 40 of the control valve $-C$. Said body member 40 is carried on a plate 42 secured to the windshield post $-P$ and is equipped with a central stud 43 which projects through and positions the rotary member 44 of said control valve $-C$, a washer and nut 45 on the end of said stud serving to engage the part 44 and retain the same in rotative relation, while handle 46 serves to produce rotation. Said rotary control member of disc 44 is provided on its inner face with an annular suction-receiving groove 48 having a plurality of radially extending branches 50, 52 and 54 which are adapted to register respectively with the control ports $-R''$, $-L''$, and $-S''$, the branch 50 also being adapted to register with port $-N''$. Groove 48 is permanently in communication with a port $-E$ in the body member 40, which port $-E$ is continuously under the influence of suction during the operation of the automobile engine, this influence being conveyed by a connection $-E'$ which leads from the intake manifold $-M$ of the engine or motor $-M'$.

Thus as the rotary control disc 44 is rotated to bring the branches 50, 52, and 54 selectively in communication with the ports $-R''$, $-L''$, and $-S''$ respectively, the corresponding conduits $-R'$, $-L'$, and $-S'$ and their ports $-R$, $-L$ and $-S$ are selectively placed under suction influences, with the result that the signal casing 18 and its blade 22 together with the signal arm 25, are brought selectively into the respective "Right", "Left" and "Stop" positions. And when the branch 50 registers with port $-N''$ (handle 46 being straight up), suction is applied to port $-N$ and the signal is returned to normal. The relative positions of these parts are indicated in Figs. 9, 10, 11, and 12.

In addition, the rotary control member 44 is provided with three vent ports $-V$, $-V'$ and $-V''$ which pass entirely therethrough and communicate with the atmosphere, the ports $-V$ and $-V'$ being symmetrically located with respect to branch 50. When the parts are in "Right" position, the port $-V$ registers with port $-N''$ and thereby admits atmospheric pressure through port $-N$ so that the signal parts may be moved readily to operative position under influence of suction applied through branch 50 to port $-R''$ and thence to port $-R$, the blade 22 and the signal thus being fully advanced until the port $-R$ is covered and the signal stands in position to indicate "Right".

When the member 44 is moved back to neu-

tral, the port $-V'$ admits atmosphere to the port $-R''$ and thence by way of port $-R$ to the suction chamber in the signal actuating device $-A$, while the branch 50 applies suction through $-N''$ and $-N$ to the space between blades 22 and 30, thus returning the signal. When member 44 is moved to "Left" position, atmosphere is admitted through $-V'$ to port $-N''$ and thence to port $-N$, and branch 52 registers with port $-L''$ thus applying suction through $-L$ to move the signal 25 to indicate "Left". When the member 44 is moved to "Stop" position, port $-V''$ admits atmosphere to ports $-N''$ and $-N$, and the branch 54 registers with port $-S''$ to admit suction to port $-S$ and thus move the signal 25 to "Stop" position.

From the foregoing the position of the control valve parts and the relation of the ports to move the signal 25 to the various positions will be clear.

However, it is desired that provision be made for also actuating the signal to "Stop" position entirely automatically and by means of the brake pedal $-K$. For this purpose a device is provided which releasably engages the rotary control member or disc 44 to rotate the latter through the medium of said brake pedal. This device as shown is in the form of a ring 55 which rotates upon the peripheral wall of the body 40 and is retained in position between the rotary member 44 and an annular shoulder 40' of said body.

A laterally extending arm 56 on said ring receives the end of a cable 57 which passes through an expansion spring 58 mounted between the arm 56 and a lug 59 fixed on the plate 42 of the control valve, the cable then passing through a sheathing 60 and thence to an extensible spring 61 which completes the connection with the pedal. The expansion spring 58 serves to return the ring to normal position after release, while the extensible spring 61 serves to permit an additional movement of the pedal after the ring has completed its movement, the ring movements being limited by a pin 62 and groove 63 provided in the ring and body as seen in Fig. 1. The releasable detent connection between the ring 55 and the rotary member 44 consists in a bent or curved spring 64 one end of which is held in a lug 65 projecting from the ring and positioning the spring so that it normally engages lightly in a notch 66 in the rotary control member 44. When it is desired to move the member 44 manually for any of the settings, the spring easily disengages from the notch 66 and rides along the edge of said member, but when the brake pedal is actuated and the ring 55 is moved thereby, the engagement of the spring in said notch is ample to insure corresponding movement and return of the disc 44 along with the ring movements.

130

It should be noted that extremes of movement of the control disc 44 in opposite directions are the "right" and "left" positions, and in order that these exact movements may be easily accomplished, a pin 68 is provided on the inner face of the disc 44 and travels in a groove 69 in the body 40, the ends of said groove limiting the movement of the pin and hence of the disc 44. Since the movement to "Stop" is usually automatic through the ring 55 and since the movement of ring 55 is limited, this position is also easily accomplished, and return to "neutral" from "Stop" is also automatically obtained. Return to "neutral" from "Right" or "Left" is easily insured because the position of handle 46 is then straight up. If it be desired to move manually to "Stop" position, the movement can be easily approximated in that it is substantially half the movement to "Left".

In order to add further to the utility of the device, means is provided for closing a circuit to light the lamps 29 and illuminate the arrows of the signal arm, and this means comprises a series of stationary contacts 70 mounted in a block 71 of insulation carried by the base 15, and a movable spring contact 72 carried by the signal housing 18, suitable electric conductors 74 and 75 supplying these contacts. The contacts 70 are so placed as to be engaged by spring contact 72 when the signal is in any of the direction indicating positions.

Thus a complete signal for automobiles is provided for all uses, the right and left signals being automatically accomplished by the suction of the engine merely by making an easy manual setting of a control device, return from these positions being accomplished in a similar fashion, and the "stop" signal with the same mechanism may be fully automatic by reason of connection with the brake pedal.

It is to be understood that the specific constructions herein disclosed are not to be considered as limiting in any sense, but merely as illustrative of a generic invention confined only by the scope of the appended claims, it being obvious that many improvements may be made within the scope of such claims by those skilled in the art.

I claim:

1. A signal comprising a signal actuating mechanism having a suction chamber and a base, a signalling device carried by said base and having a blade movable over said base to a plurality of direction-indicating positions, said base being provided with a plurality of ports communicating with said chamber and adapted to be passed by said blade, a control device having a plurality of ports respectively in communication with the ports in said base, said control device including a movable control member having a duct in communication with suction-applying

means, said member being movable to bring said duct selectively into communication with the ports in said control device to move said signalling device selectively to its various positions, and a second control device having releasable engagement with the movable control member to move the latter to one position and releasable to permit independent movement of said member.

2. A signal comprising a signal actuating mechanism having a suction chamber and a base, said base having a plurality of ports communicating with said chamber to apply suction thereto at different effective points, a signal member connected with the mechanism and movable to a plurality of direction-indicating positions, control means for selectively applying suction to the ports for moving the signal to the respective positions, and a second control means mounted in releasable engagement with the first control means to move the latter for application of suction and to permit independent movement thereof by reason of said releasable engagement.

3. A signal having a suction chamber and a movable signal member connected with and actuated thereby to a plurality of positions, said chamber having a plurality of suction-applying ports communicating therewith, a control valve comprising a body having a plurality of ports connected respectively with the first mentioned ports, a rotary control member mounted on said body and having a suction connection adapted to be moved to communicate selectively with the ports in the body, and a second movable control member also mounted on said body and having a releasable detent engaging the first mentioned control to move the latter and releasable therefrom to permit independent movement thereof.

4. A signal comprising a signal actuating mechanism having a suction chamber and a base, a signalling device carried by said base and having a blade movable over said base to a plurality of direction-indicating positions, said base being provided with a plurality of ports communicating with said chamber and adapted to be passed by said blade, a control device having a plurality of ports respectively in communication with the ports in said base, said control device including a movable control member having a duct in communication with suction-applying means, said member being movable to bring said duct selectively into communication with the ports in said control device to move said signalling device selectively to its various positions, said base being provided with a fixed wall adjacent the neutral position of the movable blade and with an additional port adjacent said wall to be covered by the blade whereby an air cushion will be provided in the chamber formed between said wall and blade.

5. A signal comprising a signal actuating

mechanism having a suction chamber and a base, said base having a plurality of ports communicating with said chamber to apply suction thereto at different effective points,
5 a signal member connected with the mechanism and movable to a plurality of direction-indicating positions, control means for selectively applying suction to the ports for moving the signal to the respective positions,
10 a second control means mounted in releasable

engagement with the first control means to move the latter for the application of suction and to permit independent movement thereof by reason of the releasable engagement, and a connection leading from said second control means adapted to be connected with and operated by the foot brake of an automobile. 15

In testimony whereof I affix my signature.

NEWTON W. MATTHEWS.
